2,403,188

HEATING APPARATUS

Henry J. DeN. McCollum, Chicago, Ill.; Thelma McCollum, executrix of said Henry J. DeN. McCollum, deceased

Application June 17, 1942, Serial No. 447,345

2 Claims.

(Cl. 158—28)

1

My invention relates generally to internal combustion type heaters, that is, heaters in which combustion takes place in a sealed combustion chamber, and more particularly to heaters of this type for use on aircraft and other vehicles in which maximum heat production is desired from a heater of minimum size and weight.

It is an object of my invention to provide an improved heater of the internal combustion type incorporating means to secure uniform and non-explosive combustion of a combustible mixture of fuel (such as gasoline) and air.

A further object is to provide an improved internal combustion type heater which is constructed to prevent explosive combustion in the event that the flame in the heater should become accidentally extinguished.

A further object is to provide an improved internal combustion type heater having means to prevent flash-back of the flame into the conduit through which the combustible mixture is supplied to the heater.

A further object is to provide an improved internal combustion type heater which is quiet in operation.

A further object is to provide an improved internal combustion type heater which can be economically constructed, which will be highly efficient, which will operate satisfactorily under varying conditions, and which will have a long useful life.

Other objects will appear from the following description, reference being had to the accompanying drawings, in which:

Fig. 1 is a fragmentary sectional view of the heater, the sections being taken along a central longitudinal plane;

Fig. 2 is a fragmentary sectional view taken on the line 2—2 of Fig. 1;

Fig. 3 is an end elevational view taken on the line 3—3 of Fig. 1, a portion of the casing being broken away to show the igniter;

Fig. 4 is an end elevational view taken on the line 4—4 of Fig. 1;

Fig. 5 is a fragmentary sectional view to a larger scale than Fig. 1, showing particularly the shield for the igniter;

Fig. 6 is a fragmentary sectional view taken on the line 6—6 of Fig. 5;

Fig. 7 is a fragmentary transverse sectional view taken on the line 7—7 of Fig. 1; and,

Fig. 8 is a wiring diagram of the electrical components of the heater.

Heaters of the type to which my invention appertains are supplied with a combustible mixture

2

of air and fuel, such as gasoline, from a carbureting apparatus, or, when utilized on a vehicle equipped with an internal combustion engine provided with a supercharger, the combustible mixture may be drawn from the outlet of the supercharger. In Fig. 1, a valve fitting 10 has its inlet end 12 threaded for attachment to a conduit through which the combustible mixture is supplied to the heater. Within the fitting 10 is a throttle valve 14, which may be operated by a lever 16, either manually or thermostatically, to control the rate of flow of the combustible mixture to the heater.

Within the outlet portion of the fitting 10 is a flame arrester 18, which, as best shown in Fig. 2, comprises a plurality of small diameter tubes 20, which may be made of copper or other good conducting metal. The overall cross-sectional areas of the bores through the tubes 20, plus the cross-sectional area of the spaces between these tubes, is sufficiently large so that the flame arrester does not offer an undesirably high resistance to flow of the combustible mixture through the flame arrester. The tubes, however, are of such small diameter that they may act in a well known manner to prevent the propagation of a flame through the flame arrester.

The valve fitting 10 is suitably secured to the inlet boss 22 of a combustion chamber casting 24 by studs 26, a portion of the wall of a main casting 28 being clamped between the fitting 10 and the boss 22. It will be noted that the flame arrester tubes 20 are located in a cylindrical tube 30, which extends into the bore of the boss 22 and has a reduced diameter end portion 32, which projects into a combustion chamber 34 formed within the casting 24. The portion 32 is provided with a plurality of ports 36 formed by louvers 38 struck inwardly from the portion 32 to cause the combustible mixture to flow in a circular path as it leaves the ports 36. A ring 40 is located within the tube 30 to form a smooth velocity of flow increasing throat, while a cusp-shaped plug 42 is secured within the end of the projecting portion 32. By virtue of the provision of the ring 40 and plug 42, as well as the louvers 38, the mixture enters the combustion chamber with a smooth uniform vertical flow.

As best shown in Figs. 5 and 6, the combustion chamber casting 24 is provided with a sidewardly extending boss 46, which is threaded to receive an igniter plug 48, within which is located a coiled wire 50 of Nichrome or similar high resistance metal, the inner end of this coil being welded to the inner end of the plug 48 and the

outer end of this wire being secured mechanically and electrically connected to a binding post 52, which is suitably insulated from the plug 48. In order to prevent the swirling combustible mixture in the combustion chamber from too rapidly cooling the igniter coil 50 when the latter is energized, the casting 24 is formed to provide a baffle 54. This baffle is generally convex in shape to provide openings at its top and bottom for the circulation of the combustible mixture past the end of the igniter coil 50. By thus restricting the circulation of the combustible mixture past the igniter wire coil, the latter may be heated more rapidly to a temperature at which it will ignite the mixture, and, since the mixture flows past the igniter at a lower velocity, it is more susceptible to ignition. The ignition of the mixture is thus greatly facilitated by the provision of the baffle 54. This is an important factor in securing reliable ignition of the mixture at extremely low temperatures and when the mixture is supplied at less than atmospheric pressures, as when the heater is used upon aircraft flying at high altitudes.

In order to make it unnecessary to reenergize the igniter 50 whenever the flame in the combustion chamber is accidentally extinguished due to a temporary interruption in the supply of combustible mixture, or a temporary change in the proportion of fuel to air in the mixture which may render the mixture comparatively incom- bustible, there is provided a reigniter 56, which is secured to a plug 58 and extends horizontally into the combustion chamber. This reigniter is preferably in the form of a spirally coiled sheet or Inconel or similar heat and corrosion re- sistant metal.

The combustion chamber casting 24 is secured to a clamping ring 59 by a plurality of studs 60, the ring 59 having a plurality of radially extending arms 62, to which the outer casing 28 is fixed by screws 64. A heat exchanger shell 66, preferably made of copper or other good heat conductor, has its flanged end 68 clamped between the ring 58 and the casting 24, a suitable gasket 70 being provided to seal this joint. The other end of the shell 66 is brazed or otherwise suitably secured to an outlet fitting 72.

Within the shell 66 is a hollow filter and muffler structure comprising a cylindrical tube 74 having a plurality of radial ribs 76. The outer end surfaces of the ribs 76 are of the same diameter as the inside diameter of the shell 66 so that there is a press-fit contact between the ends of the ribs and the shell 66, resulting in good heat conduction between these parts. The cylindrical tube 74 has a plurality of spaced small diameter ports 78 formed therein at the bases of the grooves between the ribs 76 to provide re- stricted communication with the interior of the tube 74. The tube 74 is filled with a suitable sound and vibration damping material, such as stainless steel wool or glass wool 80. The combustion chamber end of the cylinder 74 is closed by a plug 82, while the discharge end of this cylinder is closed by a hollow generally conical end cap 84, which is suitably flanged to permit the adjacent end of the cylinder 74 to be secured thereto by a spinning operation.

A bolt 86 is riveted in the end cap 84 and projects through a suitable boss 88 formed on the outlet fitting 72; a nut 90 being threaded on this bolt to make it possible to draw the end cap 84 and parts assembled therewith into properly spaced relationship with respect to the outlet fit-

ting 72, a suitable spacer 92 being preferably pro- vided to prevent the end cap 84 from being drawn too far into the outlet fitting 72.

The outlet fitting 72 is hollowed out to form, with the outer surface of the end cap 84, a generally conical passageway 94 of limited cross-sec- tional area, which is in direct communication with a bore 96 formed in the outlet fitting 72. A restriction nozzle 98 is threaded into the outlet fitting 72 and has a generally Venturi nozzle shaped portion projecting into the bore 96. The outer end of the nozzle 98 is suitably threaded for connection to a discharge conduit.

The combustion chamber casting 24 is pro- vided with a plurality of heat radiating fins 100, while the shell 66 is provided with a plurality of generally radial fins 102, which may be brazed or, depending upon the metals used, welded to the shell. These fins 102 preferably extend into close proximity with the inner surface of the outer casing 28. The outer casing 28 is secured to the heat exchange assembly not only by the nozzle fitting 98. A suitably flanged bracket 104 is secured to the outlet fitting 72 and to the outer casing 28 (see Fig. 4). The outer casing 28 has a flange 106 at its inlet end for attachment to a blower or a conduit through which air to be heated is conveyed, and has a similar flange 107 at its outlet end for connection with a conduit for conveying the heated air to the space to be heated. The casing 28 also has a projecting por- tion 108 (Fig. 3) suitably to protect the igniter plug 48 and the electrical connections thereto and also is provided with a protuberance 110 to house an electrical connection fitting.

The temperature responsive overheat switch 124 (Fig. 8) is mounted in a tube 112 (Fig. 3), which is located between fins 102 near the com- bustion chamber. A temperature responsive igniter switch 122 (Fig. 8) may be located in a tube 114 (Fig. 1) near the outlet end of the heat exchanger, while a third temperature responsive switch may be located in a tube 116 in the heated air stream at the outlet end of the casing 28. These switches may be connected in a circuit as shown in Fig. 8, in which the heater is illus- trated as being supplied with electrical energy from a battery 118, one terminal of which is grounded. Upon closing a master control switch 120, current is supplied through a thermostati- cally operated igniter switch 122 (in tube 114) to igniter 50, the other terminal of which is connected to ground. Thermostatic switches 124 and 126 are connected in series with a solenoid operated valve 128 by which the supply of fuel mixture to the heater is controlled. The switches 124 and 126 are contained in tubes 112 and 116, respectively.

It will be apparent that upon closure of the switch 120, the igniter 50 will be energized, and, assuming that the heater is cold, the switches 124 and 126 will be closed and the solenoid valve 128 thus energized. Thus, the supply of fuel mixture is fed to the heater and ignited by the hot re- sistance wire igniter 50. As soon as the heater has attained substantially its normal operating temperature, the thermostatic switch 122 will open to cut off the current supply to the igniter. If for any reason the heater should become ex- cessively hot, as by failure of the supply of ven- tilating air forced through the casing 28, the switch 124 or switch 126 may be raised to such high temperature as to cause it to open the cir- cuit to the solenoid valve 128, whereupon the supply of fuel mixture to the heater will be in-

terrupted, and dangerous overheating of the apparatus prevented.

In normal operation, the air flow through the flame arrester 18 is sufficiently rapid and these tubes are of sufficiently small diameter that the flame from the combustion chamber cannot flash back through these tubes and the spaces between them to the inlet fitting 10. The mixture supplied through the flame arrester 18 is maintained at high velocity due to the constriction formed by the member 40, and the mixture is given a rotary component of flow by the louvre vanes adjacent the ports 36. This rotary flow results in complete mixing of the fuel and air, so that it will be substantially uniform as it meets the burning mixture in the combustion chamber. This pronounced turbulence does not, however, interfere with initial ignition of the mixture by the igniter 50 because of the protecting baffle 54, which shields the igniter from this rapid flow.

Due to the fact that the combustion chamber is L-shaped, the degree of turbulence is increased so that complete combustion takes place and there is no possibility of a stream of fuel mixture passing through the combustion chamber without burning. This is an important factor when the heater is used on aircraft flying at high altitudes. Under these circumstances, the air of the mixture is so rarefied that all conditions must be favorable in order that combustion may be maintained within the combustion chamber. The difficulty of this problem may be appreciated by the fact that a candle will not burn when in atmosphere at a pressure corresponding to that encountered by a plane flying at high altitudes. If, however, the flame in the combustion chamber should be accidentally extinguished, the reigniter 56 will be effective to reestablish combustion as soon as conditions favorable to combustion are restored, provided such restoration takes place within a reasonably short time, while the reigniter 56 is still at an igniting temperature.

The products of combustion flow through the spaces between the ribs 16, and any tendency toward oscillation or explosive combustion of the mixture, is inhibited by the provision of the muffling or sound vibration filtering chamber 20, which communicates with these passageways through the small holes 78. This muffler construction is of importance in assuring steady and uniform combustion under varying conditions of operation.

The combustible mixture leaving the passageways between the ribs 16 flows through the restricted passageway 94 at a relatively high velocity. It is of importance to reduce the volume of this passageway 72 to a minimum in order to prevent, immediately after starting operation of the heater, an accumulation of gas mixture which might be ignited by the heated products of combustion and cause an explosion. Such explosive

combustion in this passageway might cause extinguishment of the flame in the combustion chamber due to the interruption of the supply of the combustible mixture because of the increased back pressure caused by the explosion.

The gases of combustion flowing through the passageway 94 enter the Venturi-shaped passageway in the outlet fitting 98 and are conducted therefrom through any suitable conduit means to a space of lower pressure than that of the fuel mixture supply. The Venturi-shaped passageway in the outlet fitting 98 has the advantageous property of appreciably compensating for changes in relative pressure of the fuel mixture supply and exhaust and functions in a manner more fully disclosed in my prior Patent No. 2,191,173.

While I have shown and described a particular embodiment of my invention, it will be apparent to those skilled in the art that numerous modifications and variations may be made without departing from the underlying principles of the invention. I therefore desire, by the following claims, to include within the scope of the invention all such modifications and variations by which substantially the results thereof may be obtained by the use of substantially the same or equivalent means.

I claim:

1. In a heater of the internal combustion type, a combustion chamber casting having an elbow-shaped combustion chamber formed therein, an igniter receiving opening extending into said combustion chamber, an igniter element secured to said casting and communicating with said combustion chamber through said opening, a connection to one end of said combustion chamber for supplying a combustible mixture thereto, a heat exchanger, a connection securing said heat exchanger to the other end of said combustion chamber casting, and a reigniter element extending into said combustion chamber in a direction toward said heat exchanger and removable therefrom without disturbing the other connections to said combustion chamber casting.

2. In a heater of the internal combustion type having means for supplying a fuel mixture and means for withdrawing the products of combustion therefrom, the combination of a casting having an L-shaped combustion chamber formed therein and said casting forming a smaller space communicating with the combustion chamber, an electrical igniter secured to said casting and having its igniting element located in said space, and a baffle forming part of said combustion chamber casting and located in front of said space to prevent direct flow of combustible mixture from said combustion chamber to the igniter element.

HENRY J. DEN. McCOLLUM.
